KNITTING MACHINE

Stanley R. Shelmire, Laconia, N. H., assignor to
Standard-Trump Bros. Machine Company,
Laconia, N. H., a corporation of Delaware

Application July 8, 1933, Serial No. 679,511

16 Claims. (Cl. 66—140)

This invention relates to a knitting machine and specifically to a knitting machine for making a rotary split foot stocking having the leg and instep portions decorated by wrapping.

5 In forming a split foot by rotary knitting it is desirable to clamp and cut each yarn after the completion of every half course so as to avoid long transverse floats which would have to be finally removed. Ordinarily this involves no 10 difficulty, the clamping and cutting means being located within the needle circle and suitable means being provided for repeatedly reintroducing the instep and sole yarns to the needles, the last means comprising merely a control for the 15 yarn fingers, which, when they move into active position, cut their yarns between the needles since the yarns extend outwardly from the inside clamp and cutter mechanism.

The manipulation of yarns for the production 20 of a rotary split foot with automatic prevention of floats is not so simple in a machine which is arranged to produce embroidery striping by the use of wrap yarns. The warp yarns extending from the needles to the wrap fingers form a cage 25 within which there cannot be any main yarn handling mechanism. Consequently all of the mechanisms for clamping and cutting the main yarns and introducing them to the needles must be located outside the needle circle or at least outside the cage of wrap yarns.

It is the broad object of the present invention to provide a knitting machine for the production of stockings having rotary knit split foot portions in which floats of the component yarns 35 are avoided and at the same time having designs formed therein by embroidery striping, which designs extend through the instep portion of the split foot.

Other objects of the invention, relating particularly to details of mechanism whereby the main object may be accomplished, will be apparent from the following description read in conjunction with the following drawings in which—

45 Fig. 1 is an elevation, partly in section, showing the portion of a knitting machine adjacent to the top of the needle cylinder;

Fig. 2 is a horizontal section showing the elements associated with the needle cylinder;

50 Fig. 3 is a vertical sectional view showing the wrap finger carrier and controlling elements for the wrap fingers;

Fig. 4 is a horizontal sectional view showing the same subject matter;

55 Fig. 5 is a sectional view showing the main

yarn fingers and the main clamping and cutting mechanism together with their actuating devices;

Fig. 6 is a plan view of the same;

Fig. 7 is a fragmentary detail showing controlling means for one of the main yarn fingers;

Fig. 8 is a horizontal section showing particularly the main clamping and cutting mechanism and the parts associated therewith.

Fig. 9 is a sectional view showing the relationship of the main yarn handling mechanism and the auxiliary cutting and clamping mechanism with the latch ring;

Fig. 10 is a perspective view showing the main 10 yarn handling devices;

Fig. 11 is a sectional view showing in detail the means for introducing yarns to the needles;

Fig. 12 is an elevation showing the auxiliary 15 clamping and cutting mechanism;

Fig. 13 is a vertical section through the needle 20 cylinder showing the relationships of a needle, jacks and associated mechanism, and

Fig. 14 is a diagrammatic illustration of a portion of a stocking formed in accordance with the 25 invention.

In the embodiment of the invention which is illustrated there is provided a needle cylinder 2 provided with the usual vertical slots in which are slidably mounted needles 6 having butts 8 of different length in the usual fashion so that 30 differentiation between the needles may be made in the production of various parts of the stocking. Beneath the needles are located upper jacks 10 provided with butts 12. Beneath these jacks and also within the slots of the needle cylinder 35 are located jacks 14 provided with removable butts 16 adapted to be acted upon by selecting cams 17 to cause the jacks to be rocked about their pivots indicated at 19. The cams 17 serve to rock the lower ends of the jacks 14 inwardly 40 so that they avoid engagement of ledges 18 formed at their lower ends with a cam provided to lift them for the taking of wrap yarns. A cam 21 serves to rock the jacks in the opposite direction about the pivot formed at 19. The particular selection of needles for the production of wrapped patterns does not form a part of the present invention and is well known, being illustrated in my prior application, Serial No. 623,057, filed July 18, 1932. For the purpose of the pres- 50 ent case it will be sufficient to state that selective wrapping is effected by the selective raising of needles at a predetermined point to take yarns from the wrap fingers.

The needle cylinder has secured thereto the 55

usual gear 20 which is driven through an idler by the usual main driving gear which is controlled by suitable mechanism of the usual type to provide both rotation and reciprocation of the needle cylinder.

- 5 The frame of the machine includes a platform 24 which supports a bracket 26 carrying a shaft 28 upon which the latch ring supporting bracket 30 is pivoted, this bracket carrying a latch ring 32. The supporting bracket has pivoted to its forward portion a hook 34 engageable with a pin 36 carried by an upstanding bracket 38 to maintain the latch ring in its lowered position. Manipulation of the hook 34 will release it from the pin 36, whereby the latch ring may be raised in the usual manner, a suitable spring being provided to counterbalance its weight and tend to hold it open. The usual sinker cap 40 containing the cams for controlling the sinkers is provided, the cap having the usual freedom for oscillatory movement limited by engagement of stops with the bracket 38. The sinker dial is indicated at 41 and rotates in the usual fashion with the needle cylinder.
- 10 A bracket 42 pivoted on shaft 28 is provided at its forward end with a downwardly extending portion 44 provided with openings through which project headed screws designed to thread into the latch ring supporting bracket 30. A spring 43 counterbalances the weight of the bracket 42 so that this bracket will tend to remain in its open position, as indicated in Fig. 1, except when held down by the screws. It may, however, be raised together with the latch ring by manipulation of the latch 34.
- 15 There is journaled in the bracket 42 a wrap yarn finger carrying head indicated at 46 which is driven in unison with the needle cylinder through gearing and a splined shaft provided with universal joints so that driving connection is not interrupted when the bracket 42 is raised. Instead of being forced to rotate continuously in fixed relationship with the needle cylinder, the head 46 may be driven through mechanism which permits its being shogged relatively to the needle cylinder to produce zigzag wrapped designs.
- 20 The head 46 is provided with axially extending slots in which are mounted wrap fingers 48 provided with projecting bearings which permit them to be rocked inwardly or outwardly between the needles of the needle circle when acted upon by cams 52 and 54 which engage butts carried by the fingers. The fingers are held in their proper positions in the head by means of a spring band 50. The cams 52 and 54 serve to rock the lower ends of the wrap fingers outwardly through the needle circle. A fixed cam 56, which engages the wrap fingers below their pivots, serves to return them inwardly of the needle circle, thus completing a wrapping operation, since the lower ends of the wrap fingers are skewed to cause them to move outwardly on one side of their cooperating needles and inwardly on the opposite side.
- 25 The cams 52 and 54 may be selectively moved into operative positions, from which they are urged by springs 62, by the action of levers 58 and 60 controlled by upwardly extending levers 64 and 66 which are in turn controlled from the main cam drum through suitable levers indicated at 67 in Fig. 2. The control of the wrap fingers is described in greater detail in my prior application referred to above. Their control is indicated in the present case merely to show the operation of wrapping, which, as will be seen here-

after, interferes substantially with a simplified control of the main yarns to form a split foot stocking.

5 The levers 67 indicated in Fig. 2 and referred to above are provided with tubular shafts which are nested with one inside the other. Within the innermost extends a third shaft 68 subject to control from the main cam drum and carrying at its upper end a lever 70 to which further reference will be made hereafter.

10 Referring now to Figs. 5-10, there are shown therein three yarn carrying fingers indicated at 72, 74 and 76. The three of these fingers are journaled independently upon a fixed shaft 78. Finger 72 is provided with a downwardly extending tail portion 80 arranged to be engaged below the pivotal point of the finger by a lever 82, the lower end of which is engaged by an upwardly extending arm 84 urged by a spring 86 into engagement with a stop screw 88, this arm 84 being pivoted at 90 to a sleeve 92 pivoted upon a fixed stud 94. A spring 96 urges the arm 84 counter-clockwise, as viewed in Fig. 5, to bring it into position for engagement by a cam 98 carried by the sinker dial 41 and arranged at predetermined intervals during the rotation of the needle cylinder to force the lever 84 clockwise, as viewed in Fig. 5, to rock the lever 82 and thereby raise the yarn finger 72 out of action. At certain times it is desired to avoid engagement of the arm 84 by the cam 98. To effect this result there is provided a wire 100 connected at one end to the arm 84 and at its other end to the lever 70. By the action of suitable cams on the main cam drum the lever 70 may be rocked to pull the arm 84 forwardly, as viewed in Fig. 5, out of the path of the revolving cam 98.

15 In addition to the control of the yarn finger 72 by the lever 82 there is an independent control for moving the yarn finger out of action in the form of a lever 102 which engages an extension of the yarn finger 72 outwardly beyond its pivot so as to force it out of action irrespective of the position of the lever 82. A detent 104, urged downwardly by a spring 106, engages within notches 108 of the lever 102 to yieldingly hold the latter in alternative positions. A downward extension 108 of the lever 102 is engaged by a forked lever 110 which is subject to yarn changing pattern control to render the finger 72 inoperative at certain times. The mechanism for actuating the lever 110 will not be described in detail, since it is identical with that disclosed in the patent to Harold E. Houseman, No. 1,161,677.

20 The yarn finger 74 is provided with a gear segment 112 meshing with a segment carried by a lever 114 generally similar to lever 102 heretofore described and similarly provided with a downward extension engaged by a forked lever 116 similar to lever 110 and controlled in the same fashion by a mechanism such as that described in the Houseman patent just referred to.

25 Yarn finger 76 is provided with a depending tail portion 118 engageable by the upper end of a lever 120 provided with a cam follower 122 engageable by a cam 124 carried, like the cam 98, by the sinker dial 41. The two cams 124 and 98 are arranged so that the fingers 72 and 76 are alternatively in operation, the operation being such, however, that there is an overlap on several needles, say three, on each side of the stocking so that the yarns carried by these fingers are tied together in the same loops in these places. The specific operation will be referred to in greater detail hereafter.

A spring 126, similar to the spring 83 which urges the finger 72 normally into active position, is connected to the rear end of the finger 76 to likewise normally urge it into active position. A lever 128, similar to 102, is arranged to engage the finger 76 to move it to an inactive position, this lever 128 being yieldingly held in alternative positions by a spring pressed detent 130 and having a lower extension 132 engaged by the forked upper end of a lever 134 forming one of the series including levers 110 and 116.

Located adjacent the finger 76 is the fixed blade 138 of the main clamping and cutting mechanism. The movable blade cooperating with this fixed blade is illustrated at 138 and is journaled upon a stud 139 being provided with a slot 140 within which projects a pin 142 carried by the lever 144 which is urged in a counterclockwise direction, as viewed in Fig. 8, by springs 146 about its pivot 148 which is in the form of a stud secured to the latch ring supporting bracket 30. A depending arm 150 of the lever 144 is engageable by an upwardly extending arm 152 of a lever pivoted at 154 to the frame and provided with a pin 156 engageable by a collar carried by a slideable plunger 158 which is arranged to be moved upwardly at proper times by a cam on the main cam disc of the machine. It will be seen that when the plunger is moved upwardly the pin 142 is moved downwardly and hence the movable knife 138 is moved to its open position. The main clamping devices include a clamping blade 160 carried by the movable knife blade 138 and a stationary clamping blade 162 which is arranged to extend between the two movable blades as indicated in Fig. 10 and is urged yieldingly against the movable blade 138 by adjustment of screw 163, this action being as indicated in the patent to H. E. Houseman, No. 1,942,816, dated January 9, 1934. The interleaving action thus provided insures a positive clamping of the yarn.

A carrier lever 164, supporting a hook 166, is pivoted on the fixed stud 168 and is provided with a slot 170 within which extends a pin 163 carried by a depresser 172 which is pivoted on the fixed shaft 78, the connections being such that the lever 164 is swung to carry yarn across the needle circle as the depresser moves down. The depresser 172 is provided with a segment 176 meshing with a cooperating segment carried by a lever 174 which has a depending extension engageable by a forked lever 178 similar to those previously indicated at 110, 116 and 134. All four of these form a single series adapted for control by the mechanism of the Houseman patent. A spring 179 normally urges the lever 174 in a counterclockwise direction so as to raise the active end of the depresser 172.

A slot 180 is provided in the latch ring extending diagonally upwardly as shown towards the position assumed by the eye in the finger 76 when that finger is raised to its inactive position. The purpose of this slot will be brought out hereafter.

A lever 182 is pivoted at 184 to the frame and is connected by a link 186 with a lever 188 actuated by cams on the main cam drum of the machine. A spring 185 normally urges the lever 182 in a counterclockwise direction as viewed in Fig. 2 against the normal tension of the link 186. Secured to the lever 182 is an upwardly extending post 183 on which is clamped a bracket 190 carrying a pivot pin 192 on which is mounted a lever 194 provided with a cam following end 196 arranged to be engaged

by cams 198 carried by the sinker dial 41, these cams being located approximately 180° apart to effect operation as described hereafter. The upwardly extending arm of the lever 194 carries an adjustable pad 200. A light spring 202 normally urges this lever in a counterclockwise direction as viewed in Fig. 12 to take up play although a stronger spring referred to later tends to hold the lever in a clockwise position so that the follower 196 is normally engageable by the cams 198.

Journalled on the post 183 is a sleeve 204 which carries a bracket 206 carrying the auxiliary clamping and cutting elements. A spring 208 urges the sleeve 204 in a counterclockwise direction as viewed in plan to bring an adjustable stop screw 212 into engagement with a post 210 carried by the bracket 190. The purpose of this, as will be evident hereafter, is to prevent damage in case of the accidental engagement of a high riding needle with the auxiliary clamping and cutting mechanism.

A slide 214 is mounted in the bracket 206 and is urged to the right as viewed in Fig. 12 by a strong spring 216 capable of overcoming the action of the spring 202. At its forward end the slide 214 is provided with a finger 218 which engages butts 228 carried by movable blades 222 and 224 associated with fixed blades 220 and 226. The blade 222 is a clamping blade having an end of L formation so as to hook and engage yarns as hereafter described. The blade 224 is a knife blade cooperating with the fixed blade 226 to sever the yarns. During the formation of the high splice and splitfoot portions of the stocking the auxiliary clamping and cutting mechanism just described is actuated twice during each revolution of the needle cylinder. At other times it is taken out of action while clamping and holding a yarn by the movement of the lever 182 in a counterclockwise direction as viewed in Fig. 2 by which action the follower 196 is taken out of the path of the rotating cams 198.

The present machine has many features in common with the machine of my prior application referred to above. It is, for example, designed to form gussets in the toes of stockings and for this purpose is provided with suitable cams indicated at 230 in Fig. 2. Since, however, the formation of the gusset has no substantial relationship to the present invention, the action of the machine in this respect will not be described in detail but reference may be made to said prior application for such features of operation.

The product of the present machine is indicated in Fig. 14. The leg portion of the stocking indicated at A is decorated by embroidery striping as indicated at B, this striping extending from the leg into the instep. A high splice is produced at C by rotary split fabric formation, the leg yarn being continued into the instep while the sole yarn is used to form the high splice, these yarns being alternately brought into action and being tied together by a relatively slight overlap as indicated at F preferably on about three needles on each side. Following the formation of the high splice C a yarn change is effected and the heel D is knit. Thereafter the foot portion of the stocking is formed by the same rotary split knitting as was previously used to form the high splice. Following the formation of the foot the advanced toe is knit after a yarn change to the heel yarn and then the toe G is formed including the gusset indicated at H.

The operation of the machine to produce this product will now be described. The yarn finger 72 carries the main leg yarn. The yarn finger 74 carries the heel yarn used for the knitting of the heel and toe. The finger 76 carries the sole yarn which is used for the formation of the high splice and sole.

During the formation of the leg the finger 72 alone is active. In order to prevent its being vibrated the lever 84 is withdrawn, by the action of the lever 70, from the path of the cam 98. The finger 74 is held inactive by the position of the lever 114 under the control of 116. The heel yarn extending therefrom is held by the main clamping mechanism consisting of the blades 160 and 162. The sole yarn finger 76 is held inactive by the action of the lever 128 under the control of 134. The yarn from this finger lies within the slot 180 and is held by the auxiliary clamping and cutting mechanism which is retracted by the counterclockwise position of the lever 182. By reason of this retracted position the follower 196 is held out of the path of the cams 198. The location of the sole yarn in slot 180 insures against its accidental engagement by the needles which pass close to the inside of the latch ring, being depressed in the stitch drawing operation below the active position of the auxiliary clamping and cutting mechanism. During the formation of the leg both cams 52 and 54 are in active position to produce embroidery striping both at the front and back of the stocking.

When the high splice is to be made, one of the cams actuating the wrap fingers, say 52, is rendered inactive, this cam being the one which acts upon the butts of wrap fingers associated with the needles which knit the heel and sole of the stocking. By rendering this cam inactive wrapping is interrupted at the rear of the stocking but is permitted to continue in the front. Alternatively the sole needles may be caused to fail to take wrap yarns by a failure to elevate them at the wrap point, this being effected by suitable trick wheel control as in my prior application referred to above. The auxiliary clamping and cutting mechanism is now brought back to active position and the finger 76 is released by the lever 128 and is thus permitted to come into action. It is now under the control of the lever 120 acted upon by the cam 124. The lever 84 is also brought into action so that vibratory movements are imparted to the yarn finger 72 as determined by the action of the cam 98. The main clamp and cutter still holds the heel yarn carried by the inactive finger 74.

During the formation of the high splice portion of the stocking by rotary knitting the two fingers 72 and 76 are alternately brought into action, the cams 98 and 124 being so arranged as to produce this alternate action but, nevertheless, permit both fingers to feed the same limited number of needles on both sides of the stocking to produce the necessary overlap indicated at F in Fig. 14. This overlap, as stated previously, is preferably on about three needles on each side. The auxiliary clamping and cutting mechanism is operated in timed relationship to the movements of the yarn fingers 72 and 76 to cut and clamp and properly release both of the yarns at the proper times. This action is effected by a proper disposition of the cams 198 carried by the sinker dial.

Even though the auxiliary clamping and cutting mechanism and also the yarn fingers 72 and 76 are substantially entirely outside the needle

circle, although the auxiliary clamping and cutting mechanism may extend to some slight degree over the needles which are being drawn down so long as it does not interfere with the yarns extending from the wrap fingers to the needles, no difficulty is experienced in securing a proper engagement of the yarns by the needles due to the fact that in view of the angular spacing of the auxiliary clamping and cutting mechanism from both yarn fingers the yarns extend in chordal relationship to the needle circle and are hence readily engaged. During the formation of the high splice the needles forming the front of the stocking are wrapped to form a continuation of the pattern of the leg through the instep.

When the heel is to be formed reciprocatory motion is imparted to the needle cylinder and the instep needles moved out of action, the sole needles alone continuing to function in the usual manner producing narrowed and widened segments to form the heel. A yarn change takes place at this time. During this yarn change which involves the bringing of the finger 74 into action and the taking of the finger 72 out of action, in order to properly introduce the yarn from the finger 74 to the needles, use is made of the yarn placing mechanism indicated in Fig. 11. The heel yarn extending between the finger 74 and the main clamping mechanism is engaged by the forward end of the presser 164 and engages within the hook 166 carried thereby. This hook carries the yarn across the needle circle to a slight extent which is insufficient to permit interference with the cage of wrap yarns. The depresser 172 simultaneously lowers the portion of the yarn extending from the finger 74 to the hook 166 and thereby insures its engagement by the proper needle. As the last course of the instep (prior to the knitting of the first heel course) is being knit by the yarn from finger 72, lever 84 is withdrawn. Finger 72 is then under the control of the main yarn changing mechanism, and after heel yarn in finger 74 has been introduced, the instep yarn is withdrawn to pass into the main clamp and cutter. As finger 72 is raised, sole finger 76 is also elevated by the main yarn changing mechanism to pass into the auxiliary clamp and cutter, after which this clamp and cutter is swung outward to draw the sole yarn into slot 180 where it will be guarded from needles during heel and toe knitting. Wrap finger controlling cam 54 is now rendered inactive in addition to cam 52 which was rendered inactive at the beginning of the high splice. The formation of the heel then takes place in the usual fashion.

After the heel is completed the parts are brought back into the positions assumed during the formation of the high splice, patterning being continued through the instep and the fingers 72 and 76 being alternately brought into action as in the formation of the high splice. When the leg yarn finger 72 is initially brought into action the placing mechanism of Fig. 11 is again utilized to insure initial engagement of this yarn with the needles.

When the advanced toe is to be formed yarn changing and operation of the parts takes place as at the beginning of formation of the heel with the exception that rotary knitting takes place on a number of courses before the beginning of reciprocatory knitting of the toe.

It will be clear that various changes may be made in the embodiment of the invention with-

out departing from its scope as defined in the following claims.

What I claim and desire to protect by Letters Patent is:

5. 1. A knitting machine comprising a circular series of needles and devices cooperating therewith for the formation of stitches, said devices including wrap fingers arranged to feed wrap yarns to the needles for the production of designs, 10 means for alternately feeding main yarns to the needles during the rotary knitting of each course of a split portion of fabric, said means being operated to produce a limited overlap of the main yarns on each side of the fabric, and means for 15 clamping and cutting the main yarns as they are taken out of action during the formation of each course.
2. A knitting machine comprising a circular series of needles and devices cooperating therewith for the formation of stitches, said devices including wrap fingers arranged to feed wrap yarns to the needles for the production of designs, the wrap yarns extending at all times in substantially straight lines from the wrap fingers to the needles, 20 means for alternately feeding main yarns to the needles during the rotary knitting of each course of a split portion of fabric, said means being operated to produce a limited overlap of the main yarns on each side of the fabric, and means for 25 clamping and cutting the main yarns as they are taken out of action during the formation of each course, said last means being located outside the path of wrap yarns extending from the wrap fingers to the needles.
3. A knitting machine comprising a circular series of needles and devices cooperating therewith for the formation of stitches, said devices including wrap fingers arranged to feed wrap yarns to the needles for the production of designs, 30 means for alternately feeding main yarns to the needles during the rotary knitting of each course of a split portion of fabric, said means being operated to produce a limited overlap of the main yarns on each side of the fabric, a main clamping and cutting mechanism, and an auxiliary 35 clamping and cutting mechanism for clamping and cutting the main yarns as they are taken out of action during the formation of each course of the split portion of fabric.
4. A knitting machine comprising a circular series of needles and devices cooperating therewith for the formation of stitches, said devices including wrap fingers arranged to feed wrap yarns to the needles for the production of designs, the wrap yarns extending at all times in substantially straight lines from the wrap fingers to the needles, means for alternately feeding main 40 yarns to the needles during the rotary knitting of each course of a split portion of fabric, said means being operated to produce a limited overlap of the main yarns on each side of the fabric, a main clamping and cutting mechanism, and an auxiliary 45 clamping and cutting mechanism for clamping and cutting the main yarns as they are taken out of action during the formation of each course of the split portion of fabric, both of the clamping and cutting mechanisms being located outside the path of wrap yarns extending from the wrap fingers to the needles.
5. A knitting machine comprising a circular series of needles and devices cooperating therewith for the formation of stitches, said devices including wrap fingers arranged to feed wrap yarns to the needles for the production of designs, 50 means for alternately feeding main yarns to the needles during the rotary knitting of each course of a split portion of fabric, said means being operated to produce a limited overlap of the main yarns on each side of the fabric, a main clamping and cutting mechanism, and an auxiliary 55 clamping and cutting mechanism for clamping and cutting the main yarns as they are taken out of action during the formation of each course of the split portion of fabric, both of the clamping and cutting mechanisms being located outside the path of wrap yarns extending from the wrap fingers to the needles.
6. A knitting machine comprising a circular series of needles and devices cooperating therewith for the formation of stitches, said devices including wrap fingers arranged to feed wrap yarns to the needles for the production of designs, a pair of yarn feeding fingers, an outside main clamping and cutting mechanism located between the yarn feeding fingers, and an outside auxiliary 60 clamping and cutting mechanism located beyond both yarn fingers in the direction of movement of the needles relative to the fingers during rotary knitting, the yarn from one of the fingers being engageable by both clamping and cutting mechanisms.
7. A knitting machine comprising a circular series of needles and devices cooperating therewith for the formation of stitches, said devices including wrap fingers arranged to feed wrap yarns to the needles for the production of designs, a pair of yarn feeding fingers, an outside main clamping and cutting mechanism located between the yarn feeding fingers, an outside auxiliary clamping and cutting mechanism located beyond both yarn 65 fingers in the direction of movement of the needles relative to the fingers during rotary knitting, the yarn from one of the fingers being engageable by both clamping and cutting mechanisms, and means for alternately bringing said fingers into action during the rotary knitting of each course of a split portion of fabric, said means being operated to produce a limited overlap of the main yarns on each side of the fabric.
8. A knitting machine comprising a circular series of needles and devices cooperating therewith for the formation of stitches, said devices including wrap fingers arranged to feed wrap yarns to the needles for the production of designs, a pair of yarn feeding fingers, an outside main clamping and cutting mechanism located between the yarn feeding fingers, an outside auxiliary clamping and cutting mechanism located beyond both yarn fingers in the direction of movement of the needles relative to the fingers during rotary knitting, the yarn from one of the fingers being engageable by both clamping and cutting mechanisms, and means for alternately bringing said fingers into action during the rotary knitting of each course of a split portion of fabric, said means being operated to produce a limited overlap of the main yarns on each side of the fabric, the yarns being clamped and cut by the auxiliary clamping and cutting mechanism during the last mentioned action.
9. A knitting machine comprising a circular series of needles and devices cooperating therewith for the formation of stitches, said devices including a pair of yarn feeding fingers, an outside main clamping and cutting mechanism located between the yarn feeding fingers, and an outside auxiliary clamping and cutting mechanism located beyond both yarn fingers in the direction of movement of the needles relative to the fingers during rotary knitting, the yarn from 70
- 75

- one of the fingers being engageable by both clamping and cutting mechanisms.
10. A knitting machine comprising a circular series of needles and devices cooperating therewith for the formation of stitches, said devices including a pair of yarn feeding fingers, an outside main clamping and cutting mechanism located between the yarn feeding fingers, an outside auxiliary clamping and cutting mechanism located beyond both yarn fingers in the direction of movement of the needles relative to the fingers during rotary knitting, the yarn from one of the fingers being engageable by both clamping and cutting mechanisms, and means for alternately bringing said fingers into action during the rotary knitting of each course of a split portion of fabric, said means being operated to produce a limited overlap of the main yarns on each side of the fabric.
11. A knitting machine comprising a circular series of needles and devices cooperating therewith for the formation of stitches, said devices including a pair of yarn feeding fingers, an outside main clamping and cutting mechanism located between the yarn feeding fingers, an outside auxiliary clamping and cutting mechanism located beyond both yarn fingers in the direction of movement of the needles relative to the fingers during rotary knitting, the yarn from one of the fingers being engageable by both clamping and cutting mechanisms, and means for alternately bringing said fingers into action during the rotary knitting of each course of a split portion of fabric, said means being operated to produce a limited overlap of the main yarns on each side of the fabric, the yarns being clamped and cut by the auxiliary clamping and cutting mechanism during the last mentioned action.
12. A knitting machine comprising a circular series of needles and devices cooperating therewith for the formation of stitches, said devices including a yarn feeding finger, a cam movable with the needles, a follower engageable by the cam and arranged to control vibration of the yarn feeding finger between active and inactive positions, means for locating the follower so it is not engaged by the cam, and additional independent means for rendering the yarn feeding finger inactive irrespective of the position of said follower.
13. A knitting mechanism comprising a circular series of needles and devices cooperating therewith for the formation of stitches, said devices including a yarn feeding finger, a cam movable with the needles, a follower engageable by the cam and arranged to control vibration of the yarn feeding finger between active and inactive positions, means for locating the follower so it is not engaged by the cam, and additional independent means for rendering the yarn feeding finger inactive irrespective of the position of said follower.
14. A knitting machine comprising a circular series of needles and devices cooperating therewith for the formation of stitches, said devices including a yarn feeding finger, a cam movable with the needles, a universally pivoted lever engageable by the cam and movable thereby in one direction to control vibration of the yarn feeding finger between active and inactive positions, and means for moving the lever at right angles to said direction to a position in which it is not engaged by the cam.
15. A knitting machine comprising a circular series of needles and devices cooperating therewith for the formation of stitches, said devices including a pair of yarn feeding fingers, clamping and cutting mechanism outside the needle circle, means for alternately bringing said fingers into action during the rotary knitting of each course of a split portion of fabric, said means being operated to produce a limited overlap of the main yarns on each side of the fabric, and means for actuating the clamping and cutting mechanism during the last mentioned action to clamp and cut yarns from both fingers when they are removed from action during the formation of each course.
16. A knitting machine comprising a circular series of needles and devices cooperating therewith for the formation of stitches, said devices including two yarn feeding fingers adapted to feed yarns to the needles, two clamping and cutting mechanisms, and control means for said yarn fingers and clamping and cutting mechanisms, said control means operating at certain periods during the formation of a stocking to cause each clamping and cutting mechanism to hold respectively one of said yarns, and said control means operating at other periods during the formation of the stocking to cause one of said clamping and cutting mechanisms to successively clamp and cut the two yarns.

STANLEY R. SHELMIRE.
